UNITED STATES PATENT OFFICE.

MEINHARD H. KOTZEBUE, OF TULSA, OKLAHOMA, ASSIGNOR OF ONE-HALF TO GEORGE S. BERRY AND ONE-HALF TO L. N. BUTTS, BOTH OF TULSA, OKLAHOMA.

ELECTRIC CLIPPER.

Application filed March 16, 1920. Serial No. 366,821.

To all whom it may concern:

Be it known that I, MEINHARD H. KOTZEBUE, a citizen of the United States, residing at Tulsa, in the county of Tulsa and State of Oklahoma, have invented certain new and useful Improvements in Electric Clippers; and I do hereby declare the following to be a full, clear, and exact description of the invention, such as will enable others skilled in the art to which it appertains to make and use the same.

This invention relates to certain new and useful improvements in electric clippers and has for its primary object, the provision of clippers which may be operated either by a direct current or an alternating current.

Another object of the invention resides in the provision of electric clippers of the above stated character in which the cutting blade may be arranged for operation in a manner similar to the conventional form of hand operated clippers and which can be effectively used for cutting hair or shearing animals such as sheep and the like.

A further object of the invention resides in the provision of electric clippers of the above stated character which may be produced for efficient operation without material alteration of the conventional form of cutter blades or plates and the spring heretofore employed for causing a return stroke of the movable cutter blade.

The invention has for a still further object, the provision of electric clippers of the above stated character which will be of simple construction and operation as well as highly efficient in use.

The invention has for a still further object, the provision of an improved electric driven device of the character stated, in which the clippers may be readily removed and other implements such as scissors, massagers, and the like substituted.

With the above and other objects in view as will appear as the description proceeds, the invention consists in the novel construction, combination and arrangement of cooperating parts as hereinafter more specifically set forth, claimed and shown in the accompanying drawings forming a part of this application and in which:

Figure 1 is a side elevation of the improved clippers.

Figure 2 is a longitudinal section through

the same, at right angles to the view of Figure 1.

Figure 3 is a detail transverse section on the plane of line 3—3 of Figure 2, looking in the direction indicated by the arrows. 60

Figure 4 is a detail sectionsl view on the plane of line 4—4 of Figure 2, looking in the direction indicated by the arrows.

Figure 5 is an enlarged detail view showing the connection between the plunger and the operating arm for the movable cutting plate or blade. 65

Figure 6 is diagrammatic view of the wiring, in order that the circuit may be traced.

Referring more in detail to the drawings, 70

in which similar reference characters designate corresponding parts throughout the several views, 1 indicates the stationary cutter blade or plate having the teeth 2 formed along its outer or cutting edge for cooperation with the cutting teeth 3 of the movable cutter blade or plate 4, in the usual manner. The cover and tension plate 5 is positioned over the movable cutter blade or plate 4 and held in position by the adjusting thumb nut 6 on the supporting post 7 which also serves to support the crank arms 8, one arm of which is engaged in the socket 9 of the movable cutter blade or plate 4 to reciprocate the latter upon the stationary cutter blade or plate 1. The remaining arm of the bell crank or crank arm 8 has a socket 10 formed therein to receive the ball or spherical end 75

of a connecting and operating rod 12, the opposite ball or spherical end 13 of which is engaged in a socket 14 formed on the end of a short threaded rod 15, the purpose of which will presently appear. The last mentioned arm of the crank arms 8 is also provided with a turned extension 16 engaged 80

in one end of a spring socket 17 formed with the stationary cutting blade or plate 1, the opposite end of which is closed by the spring adjusting screw cap 18. A spring 19 is positioned in the socket 10 and has one end bearing against the screw cap 18 while its opposite end bears against the extension 16 of the crank arm 18 to force the movable blade or plate 4 in one direction from the stationary cutting blade or plate 1, as will be later clearly understood. 85

From the socket 17 is extended an elongated arm 20 which is secured by suitable securing members 21 to the cylindrical handle 22, composed of fiber, hard rubber or 110

insulated metal, as may be desired. The arm 20 has an outwardly curved side extension 23 with which may be engaged the thumb of the operator when the fingers of the hand are clamped around the cylindrical handle 22 to prevent turning of the device in the operator's hand.

Located in the cylindrical handle 22 is the split brass tube 24, the greater portion of which is enclosed by the main or primary winding 25 having a secondary winding 26 around the same with its helix in the opposite direction, the terminals making contact so as to form a closed circuit. Extending from within the lower end of the split brass tube 24, around the primary and secondary windings of the coil, to the soft iron washers 27 to complete the magnetic circuit to the plunger, as will be later clearly understood, is the pole piece 28, composed of soft iron wire or laminated sheet steel the elements of which are preferably U-shaped as shown and the inner legs of which are shorter than the outer legs thereof. It will be evident that the purpose of the tube 24 being split is to prevent the flow of eddy currents around the wall of the tube. The pole piece serves as the magnetic conductor around the coil. The soft iron washers 27 are positioned around the split brass tube, immediately above or forwardly of the coil and are split to reduce eddy currents and serve to complete the magnetic circuit to the plunger 29 which is positioned for reciprocation in the outer or forward end of the split brass tube 24, as shown in Figure 2 of the drawings. The plunger 29 is preferably laminated and made of soft iron, the advantages of which will be apparent to those familiar with this art. The fiber base 30 is positioned in the cylindrical handle 22, around the forward end of the split brass tube 24 and contacts with the outer face of the soft iron washers 27. The fiber base 30 is secured in position by a long screw 31 or other suitable securing member engaged through the arm 20 and the side of the cylindrical handle 22 and into the fiber base 30, as shown by dotted lines in Figure 1 of the drawings.

The laminated plunger 29 has a socket 32 in its outer or forward end, within which is threaded one end of the iron screw 33, the opposite end of which is threaded in one end of the interiorly threaded brass connection 34 adapted to reciprocate through a central opening in the outer or forward cap 35 of the insulated cylindrical handle 22, the opposite end of the brass connection 34 receiving the short threaded connection 15, previously described, thereby completing the connection between the plunger 29 and the cutter blade or plate 4. Adjustably mounted upon the iron screw 33, are the fiber stroke regulating disks 36 spaced from one

another and from the end of the laminated plunger 29, by spacing nuts or jam nuts 37, also mounted upon the iron screw 33. The movable or sliding sleeve 38 of the lower movable contact member is mounted upon the lower contact post 39 having electrical connection with one pole of the core, as will be readily understood, the post 39 projecting upwardly or forwardly from the fiber base 30. The sleeve 38 has a laterally projecting finger projection 40 which extends between the fiber stroke regulating disks 36 to be engaged by the latter to move the sleeve 38 upon the post 39, as will be later clearly understood. The spring 41 is mounted upon the fiber base 30, adjacent one side of the cylindrical handle 22 and has its free end bearing against the sleeve 38 to retain the latter in adjusted position.

The sleeve 38 carries the lower or inner contact point 42 upon its outer end for engagement with the free end of the curved spring arm 43 forming a part of the remaining or upper contact member and mounted upon the contact supporting post 44. It will be understood that the electric current is supplied to the device by the conducting wires 45 extending in through the central opening 46 of the rear end cap 47 for the cylindrical handle 22, one of the wires being connected with the core and the other being preferably connected with the contact supporting post 44, although the wires may be connected in any suitable manner and lead from any suitable source of electricity. The cap 47 may be provided with an inner flange 48 for engagement in the end of the handle 22 and a stop shoulder 49 for engagement with the end of the handle 22, as shown in Figure 2 of the drawings or the cap may be of any other suitable construction and may either be frictionally engaged with the handle 22 or threaded therein if desired. The cap 47 is shown as being of semi-spherical form and provided with an insulating sleeve 50 threaded in the central opening 46 of the cap 47, around the wires 45 to protect the wires 45 from coming in contact with the cap 47, the sleeve 50 having an outwardly directed flange 51 contacting with the outwardly directed portion of the cap 47, around the opening 46, when the sleeve 50 is in position in the opening 46.

When the parts of this device are properly assembled, the space or air gap between the end of the laminated plunger 29 when in its outermost position, and the pole piece 28, should be equal to the length of the stroke of the laminated plunger 29, plus a clearance, to decrease the reluctance of the magnetic circuit to the minimum, thereby increasing the flux density or the pull on the plunger 29.

From the foregoing, taken in connection with the accompanying drawings, it is be-

lieved that the operation of this device will be readily understood, as it will be evident that when the laminated plunger 29 is drawn outwardly by the spring 19 of the clippers 5 or by a spring of the massager or other implement with which the electrically operating device is employed, the contact point 42 will be brought into engagement with the contact arm 43, thereby completing an electric circuit through the main winding 25 of the core and causing the laminated plunger 29 to be drawn inwardly. As soon as the circuit is broken, the spring will again act to throw the laminated plunger 29 outwardly. 10 This operation will be repeated, thereby causing continual reciprocation of the connecting rod 12 to properly operate the implement.

When the device is operated by a direct current, the fiber regulating disks 36 will engage the finger 40 of the sleeve 38 during each movement of the laminated plunger 29, carrying the sleeve 38 outwardly on each outward movement of the laminated plunger 25 or 29 to connect the contact points 42 and 43 and close the circuit to energize the core 25 and thereby causing the laminated plunger 29 to be again drawn inwardly, on which movement the sleeve 38 is again drawn inwardly to break the connection between the contact points 42 and 43. By constructing the device in the manner shown and illustrated, with the iron clad electro-magnet with an air gap between the 35 pole piece and plunger equal to the length of the stroke, plus a very small clearance, the reluctance of the magnetic circuit is decreased to the minimum, thereby increasing the flux density or the pull on the plunger 40 and in operation of the device the pull or flux density increases on the inward stroke, and as the work of the machine and overcoming the spring tension increases the load, the increased pull will overcome the 45 increased load in a direct ratio. Furthermore, by having the plunger pull instead of push, the spring can be used in the same place as in hand clippers in the operation of the return stroke. It will furthermore 50 be apparent that by having the plunger pull, the friction on the side and the connecting mechanism will be diminished.

By the use of the secondary coil 26 wound on the primary coil 25 with the helix in the 55 opposite direction, the terminals making contact so as to form a closed circuit, when the clippers are used on an alternating elec-

tric current and the potential of that current passes through zero on each cycle of operation a current is set up in the secondary winding which produces a magnetic flux that combines with that of the primary winding and also when the contacts are broken a momentary current is set up in the secondary, preventing the arcing across the points and transforming the current that would have been dissipated in heat in the primary winding into magnetic flux or useful energy in the secondary winding.

The device may be used on alternating currents, without alteration in the construction of the device, whenever desired or when occasion may require.

While the preferred embodiment of the invention has been disclosed, it will be understood that minor changes in the details of construction and arrangement of parts may be resorted to within the scope of what is claimed, without departing from the spirit of the invention.

What is claimed is:—

1. An actuating mechanism including solenoid winding, a plunger coacting with said winding, a plurality of magnetic elements constituting a pole piece, said elements being substantially of U-shape and embracing the winding interiorly to coact with the plunger and also embracing the winding exteriorly thereof, and a washer exteriorly of the winding to which said elements are secured exteriorly of the winding, whereby a substantially closed magnetic circuit through the plunger is provided.

2. An actuating mechanism including solenoid winding, a plunger slidably disposed in the winding, a plurality of magnetic elements constituting a pole piece, said elements being substantially of U-shape and each having one leg thereof shorter than the other leg thereof, said elements embracing the winding and the shorter leg extending interiorly thereof to coact with the plunger, said longer legs being disposed exteriorly of the winding, and a washer adjacent one end of the winding and through which said plunger slides, the longer legs of said elements being secured to said washer.

In testimony whereof I affix my signature in presence of two witnesses.

MEINHARD H. KOTZEBUE.
